UNITED STATES PATENT OFFICE.

JOSEPH J. GEDEON, OF LAKEWOOD, OHIO, ASSIGNOR TO THEODOR KUNDTZ, OF LAKEWOOD, OHIO.

CABINET FOR SEWING-MACHINES, TYPE-WRITERS, &c.

1,192,055.

Specification of Letters Patent. Patented July 25, 1916.

Application filed October 13, 1914. Serial No. 866,510.

To all whom it may concern:

Be it known that I, JOSEPH J. GEDEON, a citizen of the United States of America, residing at Lakewood, in the county of Cuyahoga and State of Ohio, have invented certain new and useful Improvements in Cabinets for Sewing-Machines, Type-Writers, &c.; and I hereby declare the following to be a full, clear, and exact description of the invention, such as will enable others skilled in the art to which it pertains to make and use the same.

This invention relates to an improved cabinet for sewing machines, typewriters, etc., in which cabinet the stationary portion comprises a horizontally arranged table-top having an opening extending vertically therethrough to permit the movement of a suitably supported sewing-machine head, typewriter or other machine through said opening into position below or above said top, and provided with a leaf hinged to said top and arranged to swing in a vertical plane, which leaf lies on said top and there extends over the hereinbefore mentioned opening, or is arranged horizontally at one end of and in line endwise with said top, according as the leaf has been swung into its extreme position in the one or the other direction.

This invention pertains more especially to a cabinet in which the hereinbefore mentioned stationary portion is provided adjacent but a suitable distance below the aforesaid top at one end of said top with a part forming a compartment and a cover is provided for said compartment.

One object of this invention is to have said cover formed by a swinging leaf which is arranged to swing in a vertical plane and connected to and smaller than the aforesaid leaf of the table-top and arranged in line endwise with the last-mentioned or larger and main leaf when the latter lies on said top and lowered, during the swinging of the main leaf into line endwise with said top, into a position in which said cover is interposed between the main leaf and the hereinbefore mentioned compartment-forming part of the stationary portion of the cabinet.

Another object is to have the aforesaid leaf of the main and larger leaf serve as a cover for the hereinbefore mentioned compartment in either extreme position of the last-mentioned leaf.

Another object is to have the smaller leaf lie on the aforesaid compartment-forming part and thereby supported from the stationary portion of the cabinet when the larger leaf lies on the table-top as well as to have the smaller leaf also lie on said compartment-forming part or stationary portion of the cabinet when the larger leaf is in line endwise with said top, and to have the relative arrangement of the parts such that, during the movement of the larger leaf into line endwise with said top, the smaller leaf is not only moved by the larger leaf but descends, and the larger leaf, when it is in line endwise with said top, lies on the smaller leaf and is consequently supported through the medium of the smaller leaf from the stationary portion of the cabinet.

Another object is to have the top surfaces of said leaves substantially in line horizontally when the larger leaf is in the position in which it lies on the hereinbefore mentioned table-top so as to form a desirable cutting or writing table, and to have the smaller leaf capable of being swung upwardly independently of the larger leaf to afford access to the hereinbefore mentioned compartment when the larger leaf is in said position.

Another object is to exclude dust, etc., from said compartment in the elevated position of the cover for said compartment when the larger leaf is in the position in which it lies on the hereinbefore mentioned table-top.

With these objects in view, and to the end of attaining any other advantage herein-after appearing, this invention consists in certain features of construction, and combinations and relative arrangement of the parts hereinafter described in this specification, pointed out in the claim, and illustrated in the accompanying drawings.

In said drawings, Figure 1 is a top plan of a cabinet embodying my invention. Fig. 2 is a vertical section on line 2—2, Fig. 1. Fig. 3 is a vertical section corresponding with Fig. 2, except that in Fig. 3 the leaf of the table-top is shown as having been actuated outwardly and into line endwise with said top and the cover of the hereinbefore mentioned compartment is in its lower position, whereas in Fig. 2 said leaf of the table-top is shown as lying on said top and said cover is shown in its elevated

position. Figs. 2 and 3 are drawn on a larger scale than Fig. 1.

Referring to said drawings, A indicates a laterally facing vertically arranged leg or supporting member of the stationary portion of a cabinet embodying my invention, which cabinet comprises a horizontally arranged table-top B extending over and resting on said supporting member and having an opening b extending vertically through said top. As shown, the supporting member A is arranged under the left-hand end portion of the top B.

C indicates a swinging leaf which has its axis arranged horizontally and transversely of the top B at the left-hand end and upper surface of said top and is arranged to swing in a vertical plane. Preferably the leaf C is hinged to said top at the left-hand end and upper surface of the top B by hinges 5 having their axes arranged horizontally and longitudinally of the left-hand edge of said top at the upper surface of said top so that said leaf is in position at the one or the other side of its axis according as the leaf has been swung into its extreme position in the one or the other direction. Figs. 1 and 2 show said leaf as lying on the top B and extending over the opening b in said top. Fig. 3 shows said leaf as having been swung outwardly from the top B and into a position in which it is arranged at the left-hand end of and in line endwise with said top.

The stationary portion of the cabinet is provided at the left-hand or outer side of the supporting member A, adjacent the axis of the leaf C, but a suitable distance below the top B, with a part a projecting laterally of and outwardly from the outer side of said supporting member and having a compartment 6 extending to the upper extremity of said laterally projecting part of the stationary portion of the cabinet and covered by a leaf E which is hinged to the leaf C, adjacent the axis of the last-mentioned leaf, by suitably applied hinges 7 which have their axes arranged parallel with the axis of the leaf C. It will be observed therefore that the leaf E is arranged to swing in a vertical plane, and I would here remark that said leaf is smaller longitudinally of the cabinet than the leaf C and that the relative arrangement of the parts is such that the smaller leaf E is arranged horizontally and in line endwise with the main or larger leaf C and has its top surface flush or in line horizontally with the top surface of the larger or main leaf C when the latter is in the position in which it lies on the top B, and that the smaller leaf E, when the larger leaf C has been swung into the position in which it is arranged at the left-hand of and in line endwise with the top B, as shown in Fig. 3, is arranged horizontally under the larger leaf

C and interposed between the latter and the upper end of the compartment-forming part a of the stationary portion of the cabinet and extends across said compartment-forming part of the cabinet. It will be observed therefore that the smaller leaf E forms a cover for the compartment 6 in either extreme position of the larger leaf C, and that the smaller leaf E descends during the movement of the larger leaf C from the position shown in Fig. 2 into the position shown in Fig. 3 and is of course elevated from the position shown in Fig. 3 into the position shown in Fig. 2 during the movement of the larger leaf C from the position shown in Fig. 3 into the position shown in Fig. 2.

The smaller leaf E is provided at its under side with an apron e embracing the compartment-forming part a at the stationary portion of the cabinet upon the descent of said leaf into the position shown in Fig. 3 and extending at its ends in the lower position of said leaf rearwardly and forwardly of said compartment-forming part to the hinged or inner end of said leaf and abutting against the left-hand or outer side of the supporting member A of the stationary portion of the cabinet so as to brace said leaf from said member of the stationary portion of the cabinet, and the apron e serves as a guard arranged to prevent dust, etc., from passing into the compartment 6 at the upper end of said compartment in the elevated position of the leaf E, shown in Fig. 2, but said leaf, when it is in its last-mentioned position in which the leaves C and E are arranged in line horizontally as shown in Fig. 2, is free to be swung upwardly and inwardly toward the table-top independently of the larger leaf C to afford convenient access to said compartment.

Preferably the compartment-forming part a of the cabinet is provided at its upper end with a laterally and outwardly projecting member or portion 8, and the apron e is provided at its lower end with a laterally and inwardly projecting member or portion 9. It will be observed that when the larger leaf C lies on the table-top B the apron e rests at its inwardly projecting member 9 on the outwardly projecting member 8 of the compartment-forming part a of the stationary portion of the cabinet so as to adequately support the smaller leaf E from the stationary portion of the cabinet in the upper position of said leaf, as shown in Fig. 2; that the relative arrangement of the parts is such that during the movement of the larger leaf into line endwise with the table-top B the apron e moves off the compartment forming part a of the cabinet and descends; that the smaller leaf lies on said compartment-forming part of the cabinet in the lower position of said leaf, as shown in Fig. 3, and that in said position of the

smaller leaf the member or portion 9 of the 5 apron *e* is arranged under and spaced downwardly from the member or portion 8 of the stationary part *a* of the cabinet, and that the larger leaf lies on the smaller leaf when the larger leaf is in line endwise with the 10 table-top so that the larger leaf is adequately supported from the stationary portion of the cabinet when it is in position 15 in line endwise with said top.

What I claim is:—

In a cabinet of the character indicated, a 15 stationary portion comprising a table-top, a leaf hinged to said top and arranged to swing in a vertical plane, which leaf lies on said top, or is arranged in line endwise with said top, according as said leaf is in the one or the other of its extreme positions, and another leaf which is smaller than and 20 operatively connected to the first-mentioned and larger leaf and adapted to be lowered or elevated during swinging of the larger leaf in the one or the other direction, the stationary portion of the cabinet having a compart-

ment-forming part which extends under the 25 smaller leaf in either extreme position of the larger leaf and is provided at its upper end with a laterally and outwardly projecting member and covered by the smaller leaf in either extreme position of the larger leaf, 30 said smaller leaf having an apron which embraces said compartment-forming part in the lower position of said leaf and is provided at its lower end with a laterally and inwardly projecting member, and the relative arrangement of the parts being such 35 that the said apron rests at its aforesaid inwardly projecting member on the aforesaid outwardly projecting member of the compartment-forming part in the upper position of the smaller leaf.

In testimony whereof, I sign the foregoing specification, in the presence of two witnesses.

JOSEPH J. GEDEON.
